UNITED STATES PATENT OFFICE.

REUBEN E. BECHTOLD, OF FORT WAYNE, INDIANA, ASSIGNOR TO WAYNE OIL TANK & PUMP COMPANY, A CORPORATION OF INDIANA.

DISPENSING-PUMP.

1,188,030.

Specification of Letters Patent. Patented June 20, 1916.

Application filed July 17, 1915. Serial No. 40,367.

To all whom it may concern:

Be it known that I, REUBEN E. BECHTOLD, a citizen of the United States of America, and resident of Fort Wayne, in the county of Allen and State of Indiana, have invented certain new and useful Improvements in Dispensing-Pumps, of which the following is a specification.

This invention relates to improvements in dispensing pumps, and the object thereof is to provide a construction for limiting the action of the pump to various predetermined portions of its normal stroke as the operator may desire so that a corresponding volume of liquid will be discharged by the pump upon operation thereof, and to so construct the device as to render its operation accurate and extremely simple.

The objects of the invention are accomplished by the construction illustrated in the accompanying drawings in which:

Figure 1 is a rear elevation of the operating mechanism of a pump with the housing thereof cut away disclosing the contained parts; Fig. 2 is a side elevation showing the exterior of the pump operating mechanism and the push-buttons for controlling the movement thereof; Fig. 3 is a detail view of the controlling mechanism 30 showing the housing for same in section and parts thereof and pump operating mechanism, also in section in several planes so as to conveniently show an assemblage of co-operating parts of the invention; and Fig. 35 4 is a view of the appliance in a plane at right angles to Fig. 3 and showing the housing in section on the line x—x of Fig. 3.

Similar characters of reference indicate corresponding parts throughout the several views and referring now to the same: (1) indicates a pump, upon which is mounted a standard (2) having at its upper end a housing (3). A pipe (4) connected at its lower end with the pump and having communication therewith extends upwardly through an extended portion of the housing and is secured therein by a set-screw (5) and affords support for the standard. The upper end of the pipe (4) is closed by a cap (6) to prevent discharge from the pump through the pipe, it being the intention that the pipe shall serve as an expansion chamber for the pump as well as a support for the housing.

55 The pump has a reciprocating pump-rod

(7) for actuating the same, and the pump-rod has fixed thereon a rack-bar (8) which has a lateral projection (9) near its lower end. A lug (10) in the housing has an adjustable set-screw (11) therein located in the path of the projection (9) on the rack-bar so that the projection will come into contact with the lower end of the set-screw and thereby stop the upward movement of the rack-bar and pump-rod connected therewith. An opening (12) in the top of the housing is made to afford access to the set-screw for adjusting the same, and a cap (13) is removably attached to the top of the housing and partially closes the opening therein so as to prevent unauthorized tampering with the set-screw. A plate (14) at the top of the rack-bar (8) and through which the pump-rod extends is adapted to contact with the top of the housing at the end of the downward stroke of the pump-rod and thus limit the downward movement thereof, there being a nut (15) on the upper end of the pump-rod to secure the plate in proper relation therewith.

A shaft (16) extends through the housing and has fixed thereon a pinion (17) within the housing, and a crank (18) upon the end of the shaft exterior thereof. An intermediate gear (19) meshes with the pinion (17) and rack-bar (8) and is mounted upon a shaft (20) that is supported in the housing. As the crank is turned the pump-rod is actuated through the medium of the pinion, gear and rack-bar.

The intermediate gear (19) has a hub (21) from the periphery of which extends lugs (22) and (23) in each of which is placed a threaded set-screw (24) and (25) respectively. A shaft (26) extends through the housing and has loosely mounted thereon a series of adjustable stops (27), (28) and (29) respectively, and connected with each of the stops is a corresponding push-rod (30) that extends through the front of the housing and has fixed upon its outer end a button (31). The several buttons bear distinguishing characters that signify the whole unit of measurement of the quantity of liquid discharged by the pump upon one cycle of its movement, or fractional portions thereof. For instance: One button bears the character 1 which may signify that the pump will operate at full stroke and that one gallon of liquid will be discharged when

the pump is operated through one cycle; another button bearing the character (½) signifies that when pressed into operating position, the pump will operate at one-half of its full stroke and discharge one-half of a gallon of liquid; and the other button bearing the character (¼) signifies that when pressed into operating position the pump will operate at one-fourth of its full stroke and discharge one-fourth of a gallon of liquid.

Each of the hinged stops (27), (28) and (29) has a slot (32) in its lower end made to accommodate a spring (33) that is coiled about the shaft (26), with one end (34) extending through an adjacent portion of the stop and the other end (35) bearing against an adjacent portion of the housing so that the action of the spring tends to hold the stop in outward or inoperative position. Each stop has also on its upper end a projection (36) and also upon its outward face near its upper end a lug (37), the latter being adapted to bear against a ledge (38) extending horizontally along the adjacent inner face of the housing when the stop is in its inoperative position. A latch (39) is hinged upon a shaft (40) that is mounted in the housing, and integral with the latch is a thumb-piece (41) that extends through a slot (42) in the housing so that the latch may be manipulated from the exterior thereof. The latch extends across the tops of the stops and is adapted to drop behind the projections (36) on the corresponding stops and hold the same in place when pressed into operative position, and said latch is adapted to be raised from engaging relation with the projections on the stops and release the same so that the stops will thereupon return to normal or inoperative position through the action of their corresponding springs, the latch being raised by manipulating the thumb-piece (41). The stops and latch are so located, and the projections on the stops are so formed that when any one of the stops is pressed into operating position, the projection thereon will bear against the latch and raise it sufficiently during its passage thereunder to release it from engagement with the projection on any other stop in the series that may have been left in operating position thus releasing such other stops so that they return automatically to inoperative position.

The lugs (22) and (23) on the hub (21) are arranged in different lateral planes and also in different radii of the hub, so that the set-screws in said lugs will engage different stops and also at corresponding different periods in the cycle of the hub. Thus, the set-screw (24) in the lug (22) will engage the stop (27), when the latter is pressed into operating position at one-fourth the stroke of the pump and arrest further discharge

action of the pump. Should the stop (28) be pressed into operating position, the stop (27) being released as the latch is raised, return to inoperative position, and the set-screw (25) in the lug (23) will engage the stop (28) at one-half the stroke of the pump and arrest further discharge action thereof. When the stop (29) is pressed inwardly the other stops are released as the latch (39) is raised and returned to inoperative position and the discharge stroke of the pump is limited by the engagement between the set-screw (11) and the lug (9) on the rack-bar. By turning the set-screws in the lugs as occasion may require the extent of movement of the pump may be adjustably regulated in each instance. Also by turning the set-screw (11) the stroke of the pump may be adjustably regulated at the end of its upward movement. Thus the pump may be made to discharge an accurate unit quantity of fluid or fractional part thereof. By pressing in the stop (29), any other stop that may be in operative position becomes released from engagement with the latch and returns to inoperative position so that the pump may be operated at full stroke. Should a fractional portion of the normal quantity of discharge be desired, one or the other of the stops may be pressed into operative position accordingly as to the amount of liquid desired, and thus the other stops are released and returned to inoperative position while the stroke of the pump is limited to a corresponding fractional portion of its normal stroke.

The purpose of the invention is to provide a dispensing pump for liquids capable of discharging selectively various quantities of liquids accordingly as may be predetermined by the operator, and to so construct the apparatus that its operation will require of the operator only the attention necessitated by the mere pushing of the plainly designated push-button and the rotation of the crank, thus reducing the chance of error upon the part of the operator.

What I claim is:—

1. In a dispensing pump, a pump proper having a pump-rod to actuate the same; a rack-bar fixed upon the rod and having at its lower end a lateral projection; a standard in fixed relation with the pump and having a housing through which the pump-rod and rack-bar extend; a lug in the housing having a set-screw therein extending in the path of the lug on the rack-bar and adapted to engage the same; a pinion within the housing having a crank in relation therewith exterior of the housing to actuate the same; an intermediate gear within the housing in mesh with the pinion and rack bar and having a hub from which a plurality of lugs extend respectively in different radii, each lug having a set-screw; a se-

ries of hinged stops within the housing, each having a push-rod attached thereto that extends through the front of the housing and terminate with a push-button bearing 5 a designating character; a spring in connection with each stop for holding it in inoperative position; and a latch within the housing adapted to engage and hold any of the stops in operative position when 10 pressed into such position.

2. In a dispensing pump, a pump proper having a pump-rod to actuate the same; a rack-bar in connection with the pump-rod; a gear in mesh with the rack-bar and having 15 a hub from which a plurality of lugs extend respectively in different radii, each lug having a set-screw; a series of hinged stops adapted to be moved severally into the path of the set-screw of the corresponding lug; 20 means tending to hold each of the stops out of operating position; and a latch adapted to engage and hold any of the stops in operative position when pressed into such position.

25 3. In a dispensing pump, a pump proper having mechanism in connection therewith including a rack-bar to actuate the same; a gear in mesh with the rack-bar having a plug with a plurality of lugs extending 30 therefrom in different planes and also in different radii, each lug having a set-screw therein; a series of hinged stops adapted to be moved severally into the paths of the set-screws correspondingly; a latch having 35 engaging relation with each of the stops; and operating mechanism to drive the gear.

4. In a dispensing pump, a pump proper having mechanism in connection therewith to actuate the same; a gear for actuating 40 said mechanism and having means in connection therewith to be driven thereby, a series of hinged stops; a latch adapted to engage any of said stops and hold same in operative position; and means in connection 45 with the gear for engaging said stops respectively at different periods in its cycle.

5. In apparatus of the class described, a pumping means including a rack-bar; a series of hinged stops adapted to be independently shifted into operative position; 50 a latch adapted to engage and detain any of said stops when shifted into operative

position; and a gear mechanism for actuating the pumping means, having means in connection therewith for engaging severally 55 said stops at different stages of its cycle.

6. In apparatus of the class described, a pumping means including a rack-bar; a series of independently operated stops; a latch for engaging and detaining any of 60 said stops when shifted into operative position; a gear mechanism for actuating the pumping means; and an engaging means in connection with the gear mechanism adapted to coöperate with the said stops accordingly as said stops are shifted, and arrest the movement of the gear mechanism at different stages of its cycle.

7. In apparatus of the class described, a pumping means; a gear mechanism having relation with the pumping means to actuate the same; a series of independently operated stops, each having a spring acting to hold the stop in inoperative position; a latch adapted to engage and detain any 75 of said stops when moved into operative position, said stops being each adapted to raise said latch from engagement with the other stops during its passage to operative position; and engaging mechanism in connection with the gear mechanism adapted to engage the stops correspondingly as the latter are shifted to operative position, said engaging means being adapted to engage the several stops at correspondingly different stages of its cycle.

8. In apparatus of the class described, a pumping means; a series of independently operated stops; a gear mechanism for actuating the pumping means and having engaging means in connection therewith adapted to contact with said stops at different stages of its cycle accordingly as said stops are shifted into operative position; and a latch adapted to detain any of 95 said stops when pressed into operative position.

In testimony whereof I affix my signature, in presence of two witnesses:
